UNITED STATES PATENT OFFICE.

KATHLEEN D. PRIMLEY, OF EVANSTON, ILLINOIS.

GOLF-BALL CARRIER.

Application filed August 25, 1924. Serial No. 733,945.

As is well known to all familiar with the pleasant and beneficial game of golf, it is necessary, for the full enjoyment of the game, that the players carry with them, in 5 addition to their golf clubs, a supply of extra balls as well as score cards and pencils for keeping their scores. It is also desirable for the comfort and convenience of the players that they shall be provided with 10 means for carrying various small personal belongings, and this is particularly necessary in the case of women players, whose apparel is ordinarily not provided with as great a number of pockets as the clothing worn by 15 men. My invention relates to a golf ball carrier which is designed to fulfill the requirements of players above mentioned, and the object of my invention is the provision of a convenient and satisfactory carrier so constructed and designed as to be particularly well adapted to answer the purposes in view and thus add to the comfort and convenience of the players and their enjoyment of 20 the game. With this object in view I have 25 invented the golf ball carrier hereinafter described in detail, the essential elements of my invention being more particularly pointed out in the appended claim.

In the accompanying drawing, Fig. 1 is a 30 perspective of a golf ball carrier embodying my invention;

Figure 2 is a vertical cross-sectional view thereof; and

Figure 3 is a rear elevation thereof.

The carrier may be conveniently formed of 35 leather, though it may also be constructed of any flexible material sufficiently strong for the purpose and sufficiently stiff to retain its shape. The general shape of the carrier is 40 oblong and rectangular and it is preferably of such size that it will receive half a dozen golf balls. On the rear wall 1 of the carrier there is provided a pocket 2 for the reception of a card or folder containing the 45 rules of the game or extra score cards, or any article of similar shape. At one end of the carrier, on the inside thereof, I have provided a pocket 3 suitable for the reception of coins, and, at the other end I have provided 50 a cross strap or pocket 4 which is adapted to retain any small article, such as a vanity box or a small folded packet of paper matches for the use of smokers. The end walls of the carrier are provided at the top 55 with inwardly folding flaps 5, and the rear

wall with a closure flap 6 equipped with a suitable snap or fastener 7. On the inside of this cover flap 6 I have provided a broad band or strap 8, suitable for the reception of a pair of gloves or a handkerchief, or for 60 a package of cigarettes.

The front wall of the carrier is provided with an outside pocket 9 which preferably and as shown, extends nearly the full length of such wall and is intended for the reception 65 of score cards. The front end of the pocket 9 is open and slightly cut away as shown, so that the score card may be readily withdrawn and replaced as the players' scores are entered from time to time at the conclusion 70 of the play at each hole. A snap member 10 arranged to cooperate with the snap member 7 before mentioned is secured to the outer face of the pocket 9. On the outside of the front end wall of the carrier I have provided two pockets 11 and 12, which in the present instance and preferably are of different depths for the accommodation of pencils of different lengths.

The carrier is intended to be carried by 80 means of a strap 13 equipped with a suitable buckle 14 or other fastening means by which it may be secured around the person of the player. This strap is arranged to run smoothly through a smooth sheath 15 secured to the rear wall of the carrier, so that the carrier may be readily slid on the belt to any desired position for the convenience of the player in removing and replacing articles or to adjust the carrier so that it will 85 not interfere with his movements in making a play.

It is obvious that some changes in the proportions of the carrier and the arrangement of the inside pockets may be made without 90 departing from the substance of my invention, and I therefore desire my claim construed to cover such immaterial changes in the construction of the parts.

I claim:

A golf ball carrier in the form of a flat rectangular box arranged to slidably engage a belt, said box having on its outer side wall a forwardly opening score-card pocket and being provided with a flexible cover flap arranged to fold downwardly upon the outer side wall of said pocket and to be detachably secured thereto.

KATHLEEN D. PRIMLEY.
